UNITED STATES PATENT OFFICE.

JOHN J. BERRIGAN, OF ORANGE, NEW JERSEY, ASSIGNOR TO HENRY R. WORTHINGTON,
A CORPORATION OF NEW JERSEY.

PRESSING APPARATUS.

1,131,032.

Specification of Letters Patent.

Patented Mar. 9, 1915.

Application filed June 16, 1914. Serial No. 845,364.

To all whom it may concern:

Be it known that I, JOHN J. BERRIGAN, a citizen of the United States, residing at Orange, county of Essex, and State of New Jersey, have invented certain new and useful Improvements in Pressing Apparatus, fully described and represented in the following specification and the accompanying drawing, forming a part of the same.

10 My invention relates to an improvement in pressing apparatus, and particularly to an improvement in a filter press of the type shown and described in my application, Serial Number 776,567, filed June 30, 1913.

15 The object of the invention is to provide convenient means whereby the filtering surface of the press may be materially increased, while at the same time allowing a free escape of the liquid from the press.

20 In my application above referred to, a press is shown comprising two platens, angularly movable about a pivotal point in the vicinity of the upper edge of the platen, said platens being so mounted that they will 25 have an angular movement toward each other, whereby the material being pressed is subjected to a pressure gradually increased from above, downward. In a press of this kind, a bag containing the material to be 30 pressed may be placed between the platens and subjected to the pressure due to the downward weight of the pressing mechanism. In such a case, where one bag is being 35 pressed, the filtering surface is the exterior surface of the bag.

By the present invention, I am enabled to employ two or more bags for containing the material, while at the same time providing a free escape for the liquid on the contiguous 40 sides of adjacent bags, and avoiding complications which might lead to an inconvenient or uneconomical operation.

With these objects in view, my invention consists in the features, details of construction and combinations which will first be described in connection with the accompanying drawings and then more particularly pointed out.

In the drawings, Figure 1 is an end view of a specific form of filter press provided with my invention; Fig. 2 a detail face view of one of the platens, with a part broken away to show one of the partition devices; Fig. 3 a detail end view, partly in section, of the same; Fig. 4 a detail cross

section of one of the partition devices; and Fig. 5 a similar view illustrating a modification of the invention.

Referring to the drawings, 1, 1^a, indicate the two platens of the press, such as is illustrated in my application hereinbefore referred to. These platens are trunnioned as indicated at 11 on arms 12 fulcrumed in suitable fulcrum devices 13. The platens are pivotally connected near their upper edges in any suitable way, as, for example, by means of the connecting devices 2, 3, 4, described in my above-mentioned application, whereby the downward movement of the platens and their attached parts, under the action of gravity, will cause the pressing faces of said platens to move toward each other, with an angular movement about an imaginary center or axis located near the upper ends of the platens. In a press of this general type, the liquid, ex, pressed from the material has a free flow downward under the action of gravity and the greater pressure above it. If, now, a plurality of bags containing material to be pressed be inserted side by side in such a press, it is obvious that the contiguous surfaces of adjacent bags will bear against each other and that, therefore, owing to the flexibility of the bags, these contiguous surfaces will fit tightly against each other. As a result of this, it has been found in practice that the amount of filtering surface does not increase in direct proportion to the number of separate bags inserted at one time in the press. By my present invention, I separate the bags by a partition device located between the contiguous surfaces of adjacent bags, the partition device or devices being mounted in such a way that the bags may be readily inserted between the respective platens, or between a partition device and a platen, while at the same time the partition devices have a certain freedom of movement, so as to permit the ready compression of the material in the bags. In the best embodiment of my invention, these partition devices are so constructed as to permit the escape of the liquid from the material being pressed, and a free flow of such liquid from each partition device.

In order to accomplish the desired results in the most satisfactory manner, each partition device comprises a plurality of plates, namely, a central partition plate arranged

to provide downward discharging liquid channels, and a pair of foraminated plates, arranged one at each side of the central partition plate.

5 In one embodiment of the invention, illustrated in Figs. 1 to 4, a central partition plate A is provided, this consisting of a plate of solid material provided with downward extending channels, which, in the 10 example shown, are formed by grooving the plate in a longitudinal direction, as indicated at a, Figs. 2 and 4, these grooves extending to the bottom of the plate A, so that the liquid may flow freely from the 15 channels. On each side of the central partition plate is placed a foraminated plate, each of which, in the present example consists of a sheet or plate of wire gauze, as indicated at A', these gauze sheets or plates 20 being secured to the central partition plate in any suitable manner, as, for example, by screws a' passing through suitable clamping strips A², which bear against the upper and lower margins of the corresponding gauze 25 sheets or plates A' and clamp the same firmly against the corresponding central partition plate A. In pressing some materials, each partition device may consist merely of a central partition plate having channels or 30 grooves, the two facing sheets of wire gauze being omitted. In using a partition device of this kind, the channels or grooves should have such a small width that the bag material will span the groove without bursting 35 under the pressure to which it is subjected, and the depth of each groove should be such that the bag will not be pressed to the bottom of the groove, but will have a portion of the channel unobstructed, so that 40 the liquid may flow freely in a downward direction.

Instead of making the central partition plate solid with grooved faces as herein-before described, it may be made of heavy 45 wire cloth or grating material, as indicated at A², Fig. 5, and to this may be suitably secured facing sheets of wire gauze, as indicated at A', Fig. 5. In this construction, the gauze sheets may be tied to the central 50 partition plate by wires, as indicated at a⁴. With a partition device thus constructed, the liquid is pressed through the foraminations in the gauze into the spaces in the heavy wire cloth or grating, and, owing to the fact 55 that these spaces communicate with each other, the liquid is free to flow downward to the bottom of the partition device and thence discharge.

Each partition device is supported at its 60 upper corners by a suitable supporting device B, in this case mounted loosely in the respective platens near the upper ends thereof. As shown, each supporting device comprises a bolt whose ends extend loosely 65 through holes in the platens, these bolts

having suitable means for preventing them from accidentally dropping from the platens. In the present instance, this result is accomplished by providing each bolt with a head at one end and a nut at the other, as 70 will be clear from the drawing. Each supporting device B passes loosely through a hole in its respective corner of the partition devices, so that the partition devices tend to hang down vertically from the supporting 75 means. While I have shown two such partition devices, it is obvious that more might be used.

In order to make it convenient to insert the bags between the respective partition 80 devices and platens, it is important that the partition devices shall not be permitted to slide over into close contact with the platens. For the purpose of preventing such contact, suitable means is provided for restricting 85 the movement of the partition devices on the supporting means. In the present embodiment of the invention, this restriction of the movement of the partition devices is readily accomplished by providing distance 90 bolts C engaging the respective partition devices near their upper corners, these bolts being loosely connected to corresponding platens. In the present example, each distance bolt passes loosely through a hole in 95 one platen and is provided with a nut beyond the inner face of said platen. Also, it passes loosely through holes in the partition devices and is provided with a suitable restricting device, such, for example, as a 100 head at its free end. This head serves to restrict the movement of the partition devices farthest from the platen to which said distance bolt is connected, so that said partition devices cannot move over in contact 105 with the platen nearest to it. By this method of mounting, the partition devices have the requisite freedom of movement, so that as the pressing operation proceeds and the material is compacted, the partition devices will be free to move as required. At 110 the same time, when the material is removed from between the partition devices and platens, there is no possibility of inconvenience resulting from the slipping of partition 115 devices in close contact with their adjacent platens.

It will be seen that where the bags are separated by partition devices, suspended loosely in the manner herein before pointed out, the bags are prevented from coming in contact with each other and hence the liquid expressed from the inner sides of the bags adjacent to each other may flow freely 120 downward in the liquid channels of the central partition plates. By providing the foraminated outer plates, the liquid may flow from the bag into such foraminations, and from there will escape into the channels of the central partition plates. By this 125 130

means, an increased filtration surface may be obtained, without a material increase in the cost of construction or inconvenience in operation, as the bags may readily be inserted and removed from the press.

What is claimed is:—

1. In a filter press, the combination, with a pair of platens having their pressing faces extending in a general upward direction, and means whereby a relative movement of said platens toward and from each other is produced, of a partition device intermediate said platens, and means carried by the platens for supporting said partition device.
2. In a filter press, the combination, with a pair of platens having their pressing faces extending in a general upward direction, and means for producing an angular movement of the platens toward and from each other, of a supporting means carried by both platens, a partition device supported by said supporting means and capable of movement with relation thereto, and means for restricting the movement of the partition device.
3. In a filter press, the combination, with a pair of platens having their pressing faces extending in a general upward direction, means for connecting said platens for pivotal movement near their upper sides, and means for producing an angular movement of the platens about said pivotal connection, of supporting means extending through and loosely mounted in each platen near its upper edge, partition devices carried by said supporting means, and means carried by each platen for limiting the movement of the partition device farthest from it.
4. In a filter press, the combination, with a pair of platens having their pressing faces extending in a general upward direction, means for connecting said platens for pivotal movement near their upper sides, and means for producing an angular movement of the platens about said pivotal connection, of supporting bolts extending through and loosely mounted in each platen near its upper edge, partition devices carried by said supporting bolts, each partition device having downward discharging liquid channels, and distance bolts carried by each platen for limiting the movement of the partition device farthest from it.
5. In a pressing apparatus, the combina-

tion, with coöoperating members mounted for gravitational movement downward and having pressing faces extending in a general upward direction, of means for causing the downward movement of said members to produce an increasing pressure on said members to move them toward each other, supporting means carried by the platens near their upper sides, and partition devices loosely hung on said supporting means.

6. In a pressing apparatus, the combination, with coöoperating members mounted for gravitational movement downward and having pressing faces extending in a general upward direction, of means for causing the downward movement of said members to produce an increasing pressure on said members to move them toward each other, supporting means carried by the platens near their upper sides, partition devices loosely hung on said supporting means, and means carried by each platen for limiting the movement of the partition device farthest from it.

7. In a filter press, the combination, with a pair of platens having their pressing faces extending in a general upward direction, and means whereby a relative movement of said platens toward and from each other is produced, of a partition device intermediate said platens, said partition device comprising a central partition plate provided with downward discharging liquid channels and foraminated plates at each side thereof, and means for supporting said partition device loosely.

8. In a filter press, the combination, with a pair of platens having their pressing faces extending in a general upward direction, and means whereby a relative movement of said platens toward and from each other is produced, of a partition device intermediate said platens, said partition device comprising a central partition plate having a plurality of narrow downward extending grooves through which liquid may discharge from the plate.

In testimony whereof, I have hereunto set my hand, in the presence of two subscribing witnesses.

JOHN J. BERRIGAN.
